UNITED STATES PATENT OFFICE.

JAMES J. McCABE, OF NEW YORK, N. Y.

DESIGN FOR A FRAME FOR STEADY-RESTS FOR LATHES.

SPECIFICATION forming part of Design No. 34,627, dated June 4, 1901.

Application filed May 1, 1901, Serial No. 58,394. Term of patent 14 years.

To all whom it may concern:

Be it known that I, JAMES J. McCABE, a citizen of the United States, residing at New York city, in the county and State of New York, have invented and produced a new and original Design for a Frame for a Steady-Rest for Lathes, of which the following is a specification, reference being had to the accompanying drawings, forming a part thereof, and in

which—

Figure 1 is a side elevation of a frame for a steady-rest bearing and incorporating my design. Fig. 2 is an elevation of the other side of same, and Fig. 3 is a top view of same.

The leading feature of my design consists of the form and configuration of the frame for a steady-rest for lathes, substantially as shown.

In the drawings, A designates the steady-rest frame as a whole, said frame comprising the base B and the substantially circular portion C, having an open center, as shown. At one side of the frame is formed the concentric flanges D E, between which are recesses F. The opposite side of the steady-rest frame

presents substantially flat surfaces, as shown in Fig. 2, with the exception of the broad radial grooves or recesses G. At its top the frame has the dome-shaped extension H, which at one side of the frame, as shown in Fig. 1, has the encompassing flange I and recess J, harmonizing with the general style of the side of the frame. The base B at one side of the frame projects laterally beyond the general vertical plane of the frame, as shown in Figs. 2 and 3, and as indicated in Figs. 1 and 2 the center of the base B is at one side of the center of the opening in the upper circular portion of the frame.

What I claim is—

The design for a frame for a steady-rest for lathes, substantially as shown and described.

Signed at New York, in the county and State of New York, this 30th day of April, 1901.

JAMES J. McCABE.
